[57] CLAIM

The ornamental design for a paint bucket, as shown and described.

DESCRIPTION

FIG. 1 is an upper front side perspective view of a paint bucket showing our new design;

FIG. 2 is a front side elevational view of the bucket shown in FIG. 1;

FIG. 3 is a right side elevational view thereof, the left side being identical thereto;

FIG. 4 is a rear elevational view thereof;

FIG. 5 is a top plan view thereof; and,

FIG. 6 is a bottom plan view thereof.

Fig. 1.

Fig. 2.
